UNITED STATES PATENT OFFICE.

HERMAN GERLING, OF ST. LOUIS, MISSOURI.

COMBINATION DIPPER AND FUNNEL.

964,908.

Specification of Letters Patent. Patented July 19, 1910.

Application filed April 15, 1910. Serial No. 555,664.

To all whom it may concern:

Be it known that I, HERMAN GERLING, citizen of the United States, residing at St. Louis, State of Missouri, have invented certain new and useful Improvements in Combination Dippers and Funnels, of which the following is a full, clear, and exact description, reference being had to the accompanying drawings, forming a part hereof.

My invention has relation to improvements in household dippers and it consists in the novel construction of dipper more fully set forth in the specification and pointed out in the claims.

In the drawings, Figure 1 is a side elevation of the dipper shown extended; Fig. 2 is a cross section on the line 2—2 of Fig. 1; Fig. 3 is a vertical middle section on line 3—3 of Fig. 1; Fig. 4 is a perspective diagram showing the manner of disposition of the wiring; and Fig. 5 is a side elevation of the dipper in its contracted or collapsed form.

The present invention though admirably adapted for use in connection with milk, cream, butter-milk and the like, may be used in dispensing any liquid and measuring specific quantities from one vessel to another. It has for its object to provide a dipper which will dispense with the necessity of tipping the dipper to pour out the contents of the same, as is usual with the prevailing milk-man's dipper. In the present improvement a valve controls a discharge opening at the bottom of the dipper, the valve being manipulated by the hand of the operator from a point above the vessel of the dipper proper.

A further object is to provide a dipper which can stand unsupported when temporarily not in service; one which may easily discharge into narrow mouthed vessels or through small openings, and one possessing further and other advantages better apparent from a detailed description of the invention which is as follows:—

Referring to the drawings, 1 represents a preferably cylindrical vessel constituting the dipper proper, the same being provided with a conical bottom 1' having a central discharge mouth or opening O. Formed about the upper edge of the vessel 1 is a bead b made by folding the metal of the vessel over a band of wire w as usual in sheet metal vessels, the wire in the present

instance after the formation of the bead, being bent upwardly in the form of a rigid handle 2. The upper end of the handle 2 is then bent outwardly in the form of a hand-hold 3 terminating in a resilient loop 4 from which it is again bent inwardly in the form of a yielding finger-hold 5, thence downwardly in the form of a yielding plunger rod 6 guided in a basal loop 7 formed in the wire portion 2. The bottom extension 6' of the plunger 6 inclines inwardly and downwardly to a point above the discharge opening O where it is connected to a rubber or equivalent valve V, normally seated over and closing the opening O under the resilient action of the loop 4. The resiliency of the loop 4 tends to diverge the finger-hold member 5 from the hand-hold member 3, and thus force the plunger 6 into the cup or dipper, and the valve V to its seat.

Loosely encompassing the vessel 1 is an outer shell or band S which hugs the walls of the vessel sufficiently to remain in whatever position it may be shifted; and if pulled or adjusted downwardly to a point to bring the lower edge of the shell in the plane of or just beyond the plane of the opening O, and then set down on a table or level surface, the dipper will stand up. To have the dipper in a standing position while being used, is a great advantage to the housewife, or milk-man, as whatever liquid may be inadvertently left in the vessel will not be spilled where not wanted; besides the standing position of the dipper is a more convenient one, as the handle is in a convenient position to be grasped and manipulated.

To use the dipper the person seizes the parts 3 and 5 between the palm of the hand and the fingers respectively, then dips the vessel 1 into the liquid to be dipped as usual. To discharge the contents of the dipper the operator squeezes the parts 3 and 5 together, and since the part 5 is the yielding member of the two, it will move toward the part 3 and lift the plunger 6. The pull on the plunger unseats the valve V and the contents will discharge through the opening O (Fig. 1). Where it is desirable to discharge the contents of the dipper into a bottle B having a neck to which the discharge end of the conical bottom 1' can be applied (Fig. 5) the shell S may be slipped back over the vessel 1, so as to be out of the way,

leaving the bottom 1' fully exposed. The device thus constitutes a combination dipper, funnel, and a measure.

Having described my invention, what I claim is:—

1. A dipper comprising a vessel provided with a conical bottom having a discharge opening, a sliding shell frictionally secured about the walls of the vessel and adapted to be slipped to bring its lower edge in the plane of the discharge opening whereby the vessel may stand up on a horizontal supporting surface.

2. A dipper comprising a vessel having a bottom discharge, a wire bead at the upper edge of the vessel, an upward extension of said bead forming a handle, an outwardly

deflected terminal forming a hand-hold and terminating in a resilient loop, an inwardly deflected finger-hold extending from said loop, a downward extension from said finger-hold forming a plunger, a valve at the lower end of the plunger normally seating over the discharge opening, and a loop formed at the base of the handle rod for guiding the plunger, the parts operating substantially as, and for the purpose set forth.

In testimony whereof I affix my signature, in presence of two witnesses.

HERMAN GERLING.
